UNITED STATES PATENT OFFICE.

HARVEY A. WREN, OF NAVY YARD, SOUTH CAROLINA, ASSIGNOR OF FORTY ONE-HUNDREDTHS TO J. L. PAUL, OF JOHNS ISLAND, SOUTH CAROLINA.

RAIL JOINT.

Application filed June 3, 1924. Serial No. 717,598.

To all whom it may concern:

Be it known that I, HARVEY A. WREN, a citizen of the United States, residing at Navy Yard, in the county of Charleston and 5 State of South Carolina, have invented certain new and useful Improvements in Rail Joints; and I do hereby declare the following to be a full, clear, and exact description of the invention, such as will enable others 10 skilled in the art to which it appertains to make and use the same.

The primary object of this invention is the provision of a rail joint which will practically possess the same resiliency as the 15 rail, thereby preventing fracture at the joint which is attributable to the usual rigid nature thereof.

In accordance with the present invention, a fishplate of angle formation has the intermediate portion of the upper edge of its 20 vertical member straight and adapted to engage beneath the heads of adjacent rail ends, said upper edge sloping from the intermediate straight portion to the ends of 25 the fishplate.

The invention furthermore contemplates a fishplate in which the lateral or horizontal member has its intermediate portion upon the bottom side hollow, whereby to 30 provide for flexing so that, as hereinbefore stated, the joint will be substantially as resiliant as the body of the rail with the result that fracture is prevented.

Other objects and advantages will be apparent and suggest themselves as the nature of the invention is understood.

While the drawings illustrate an embodiment of the invention it is to be understood that in adapting the same to meet different 40 conditions and requirements, various changes in the form, proportion and minor details of construction may be resorted to without departing from the nature of the invention.

Referring to the accompanying drawings forming a part of the application,

Figure 1 is a side view of a rail joint embodying the invention,

Figure 2 is a transverse section thereof, 50 Figure 3 is a longitudinal section through the base of the fishplate, and

Figure 4 is a detail view in perspective of the fishplate.

The numeral 1 designates the ends of adjacent rails which are adapted to be cou-

pled to form a rail joint. Similar or like fishplates are disposed upon opposite sides of the joint and overlap the rail ends to which they are bolted. Each of the fishplates comprises a vertical member 2 and a horizontal member 3, the vertical member 2 being placed against the web portions of the rail ends 1 and the horizontal portion 3 overlying the flanges at one side of the rail ends and forming the face thereof. The intermediate portion 4 of the top edge of the vertical member 2 is straight and fits snugly beneath the heads of the rail ends so as to support the joint when subject to vertical stress. Opposite end portions 5 of the top edge of the vertical member 2 slope towards the ends of the fishplate so as to provide a space between said end portions 5 and the heads of the rail ends whereby the joint is rendered resilient so as to have approximately the same yield as the body of the rail. A longitudinal rib 6 is disposed along the top edge of the vertical member 2 and extends laterally therefrom to engage the web portions of the rail ends adjacent the 75 heads thereof. It will be understood that the rib 6 reinforces the upper edge of the member 2. The angle formed by the vertical member 2 and horizontal member 3 is strengthened by rib 7, and the outer edge 80 of the horizontal member 3 has a rib 8 to stiffen and reinforce said member 3 so that it may be made of sufficiently light construction to yield. The intermediate portion 9 of the horizontal member 3 is hollow upon 85 its bottom side and comes opposite the joint formed between the base flanges of the rail ends 1, thereby materially adding to the resiliency of the joint.

In practice, a rail joint embodying the 90 invention has companion fishplates disposed upon opposite sides thereof and made secure by bolts 10 which pass through registering openings formed in the web portions of the rail ends and in the vertical members 2 of the fishplate. The horizontal members 3 of the fishplate overlying the base flanges of the rail ends are secured to the tie 11 by means of spikes 12 or other suitable fastening means.

What is claimed is:

1. A fishplate for a rail joint, the same comprising vertical and horizontal members, the intermediate portion of the top edge of the vertical member being straight 100

105

110

- and the end portions sloping outwardly in opposite directions, and the intermediate portion of the horizontal member being hollow upon its bottom side.
- 5 2. A fishplate for a rail joint, the same comprising vertical and horizontal members, the intermediate portion of the top edge of the vertical member being straight and the end portions sloping outwardly in 10 opposite directions, and the intermediate portion of the horizontal member being hol-
- low upon its bottom side, and the vertical member having a laterally disposed rib along its top edge and the horizontal member having a depending rib along its free 15 longitudinal edge portion.

In testimony whereof I affix my signature in presence of two witnesses.

HARVEY A. WREN.
